UNITED STATES PATENT OFFICE.

JAMES A. MITCHELL, OF MAGNOLIA, ARKANSAS.

WIRE-STRETCHER.

1,190,788.

Specification of Letters Patent.

Patented July 11, 1916.

Application filed September 9, 1915. Serial No. 49,809.

To all whom it may concern:

Be it known that I, JAMES A. MITCHELL, a citizen of the United States, residing at Magnolia, in the county of Columbia and State of Arkansas, have invented certain new and useful Improvements in Wire-Stretchers; and I do declare the following to be a full, clear, and exact description of the invention, such as will enable others skilled in the art to which it appertains to make and use the same.

This invention relates to improvements in wire stretchers and has for its object to provide a comparatively simply constructed device which may be very cheaply manufactured.

Another object is to provide a device of this character having a carriage on which is mounted a pair of anti-friction rollers, the stretcher bar being designed to run on these rollers.

With the above and minor objects in view, my invention consists in the novel features of construction, combination and arrangement of parts which will hereinafter be more particularly described and claimed and shown in the drawings wherein:

Figure 1 represents a perspective view of this improved wire stretcher in operation; Fig. 2 is a vertical section on the plane of line 2—2 of Fig. 3; Figs. 3, 4 and 5 are vertical transverse sections on the lines 3—3, 4—4 and 5—5 of Fig. 2; Fig. 6 is a detail transverse section on the line 6—6 of Fig. 1.

In the embodiment illustrated, I have shown my wire stretcher 1 connected by one end to a post or other stationary object P by the chain 2 which has a hook 3 on one end designed to catch a suitable clevis 4 on the wire stretcher. The opposite end of the stretcher is connected by any preferred means to a suitable wire clamp 5.

The wire stretcher comprises broadly a carriage on which is slidably mounted a stretcher bar 6. This carriage is preferably formed of a pair of U-shaped bars 7 and 8 to the outer sides of which are secured the plates 9 and 10, said stretcher bar being designed to pass between the upright arms 12 of the U-shaped members 7 and 8 and to slide on the anti-friction rollers 11 pivoted between the said arms 12 of the U-shaped members as illustrated in Fig. 2.

The rollers 11 are mounted on the pivot bolt 13 which pass through the arms 12 and through the plates 9 and 10 and are designed

to receive on their threaded ends the nuts 14. The upper portions of the plates 9 and 10 are held to the members 7 and 8 by bolts 15 and 16 passing transversely therethrough, 60 the outer ends of said bolts being provided with nuts. The bolts 15 and 16 also pass through the arms 17 of the clevis 4 and secure said clevis to the carriage.

A gravity catch 18 is pivoted on the bolt 65 15 and is designed to coact with the ratchet teeth 19 formed on the upper edge of the stretcher bar 6 and to hold said bar in operative position. An additional gravity catch or dog 20 is pivoted between the arms 21 of 70 the bifurcated operating lever 22, said lever being pivoted in the carriage between the plates 9 and 10 thereof by the bolt 23. This catch 20 may be termed for the sake of convenience, the operating or actuating catch, 75 while the catch 18 may be termed the retaining catch. The active end 24 of the dog 20 is also designed to coact with the ratchet teeth 19 on the bar 6. The outer end of this stretcher bar 6 is preferably provided with a 80 clevis 25 adapted to receive a hook 26 formed on the chain 27 which connects the wire clamp 5 to the wire stretcher 1.

In operation, the wire stretcher is connected with the wire fence, as shown in Fig. 85 1. The catches 18 and 20 are raised and the stretcher bar moved toward the post P as far as possible, the catches being then released to prevent the bar 6 from being moved to its former position by the tension 90 of the wire fence. The fence is now ready to be stretched which can be readily accomplished by moving the lever 22 from its position as shown in Fig. 1, toward the post P which will cause the active end 24 of the 95 actuating catch 20 to move the bar 6 in a direction to stretch the fence, the active end of the retaining catch sliding over the ratchet teeth 19 until the movement of the lever 22 is stopped, when said retaining 100 catch will coact with the teeth 19 to retain the bar 6 in its extended position. The lever is then moved toward the fence which will cause the active end 24 of the actuating catch 20 to slip over the teeth 19, then the 105 lever can be moved toward the post P and the stretching operation repeated. These movements of the lever 22 may be repeated until the fence has been stretched a sufficient extent.

While any preferred form of wire clamp may be used, I preferably employ that illus-

trated in Figs. 1 and 6, which comprises an upright post 28 having the flat plates 29 and 30 inset in its opposite sides. A plurality of openings are arranged through these 5 plates and the member 28 to provide for the bolts 31 which extend therethrough and clamp under their T-shaped heads 32 the strands of the wire fencing, the opposite ends of said bolts 31 being threaded and provided with nuts 33. It is evident that on 10 tightening these nuts 33 on the threaded ends of the bolts 31, that the strands of the wire fencing will be tightly clamped beneath said T-shaped heads 32.

15 From the foregoing description, taken in connection with the accompanying drawings, it is obvious that I have produced a very simply constructed wire stretcher which will be found to be extremely efficient 20 in operation.

I claim:

In a wire stretcher, a carriage comprising a pair of spaced apart U-shaped bars, spacing blocks between the free ends of said bars 25 and riveted thereto, a flat plate on the outer face of each pair of bars, a pivot bolt extending through each of said bars adjacent the bottom thereof and through said plates to secure the same in place, an anti-friction

roller on each of said bolts between the arms 30 of the bars, a clevis, the arms thereof extending across said plates adjacent their upper edges, a ratchet bar slidable on said rollers between the same and said spacing blocks, a pivot bolt extending through the 35 upper end of one of said U-shaped bars and through said plates and the ends of the clevis arms, a retaining gravity catch on said last mentioned pivot bolt between the arms of the U-shaped bar, said catch 40 operating with the ratchet teeth, an additional bolt extending through the intermediate portions of the arms of said clevis and through said plates to secure the same together, a forked operating lever, the fork 45 thereof being pivoted intermediate its ends on said last mentioned bolt between said plates, an actuating gravity catch pivoted to said lever between the arms of the fork and below its fulcrum, and a clevis on one end 50 of the ratchet bar.

In testimony whereof I have hereunto set my hand in presence of two subscribing witnesses.

JAMES A. MITCHELL.
